UNITED STATES PATENT OFFICE.

ELLIOTT B. CLARK, OF WELDON, NORTH CAROLINA.

BOTTLE CONSTRUCTION.

Application filed December 10, 1924. Serial No. 755,089.

This invention relates to improvements in bottles or similar containers, an object being to provide a bottle or the like which may be easily and thoroughly washed so as to render 5 the bottle sanitary, the construction eliminating sharp corners upon the interior of the bottle so as to reduce danger of accumulation of dirt or other injurious matter.

Another object of the invention is the provision of a bottle which is constructed so as to prevent a person from drinking directly 10 from its mouth.

Another object of the invention is the provision of a bottle having a construction 15 or configuration easily recognized so as to adapt the bottle for use as a poison container.

For the accomplishment of the above and other purposes, the invention provides a 20 bottle which may include at one or both ends, a flanged opening, the latter being also surrounded by a relatively wide flange which extends beyond the flange of the opening and provides a protector or guard for a removable closure and also prevents the 25 flanged opening from being reached by a person attempting to drink from the bottle.

With the above and other objects in view, the invention further includes the following 30 novel features and details of construction, to be hereinafter more fully described, illustrated in the accompanying drawings and pointed out in the appended claim.

In the drawings:—

35 Figure 1 is a sectional view of a bottle constructed in accordance with the invention.

Figure 2 is a bottom plan view of the same.

40 Figure 3 is a section showing a slightly modified form of the invention.

Referring to the drawings in detail wherein like characters of reference denote corresponding parts, the bottle which is especially adapted for containing soft drinks, is as shown in Figure 1, provided with a neck 10 and a mouth 11, the latter being adapted to be closed by a crown seal or other closure 12.

50 The bottom of the bottle is provided with an opening 13 which is surrounded by a flange 14, the adjacent portions of the bottom of the bottle being rounded as indicated at 15 so as to eliminate sharp corners and

prevent the accumulation of foreign matter. 55 The opening 13 is adapted to be closed by a removable seal 16, which, when removed will permit of the passage of water directly through the bottle so that the latter may be quickly and thoroughly cleaned. 60

The bottom of the bottle is provided with a flange 17 whose outer edge extends beyond the seal 16. The flange 17 is spaced from the flange 14 and forms a relatively wide base upon which the bottle may rest without having the seal 16 engage the surface upon which the bottle is placed. This prevents accidental loosening of the seal. The flange 17 is interrupted as indicated at 18 65 so as to permit of the insertion of a suitable 70 implement for the removal of the seal 16.

In Figure 3 of the drawings, the flange which is indicated at 17' surrounds and extends above the mouth 11 and prevents placing the mouth 11 to the mouth of a person 75 attempting to drink from the bottle. The flange 17' is also interrupted as indicated at 18' so that an opener may be inserted for the removal of a seal.

In addition to the advantages set forth, 80 the construction of the bottle is such as to render it easily recognizable and a person picking up the bottle in the dark would quickly recognize the same. This feature adapts the bottle as a poison container. 85

The invention is susceptible of various changes in its form, proportions and minor details of construction and the right is herein reserved to make such changes as properly fall within the scope of the appended 90 claim.

Having described the invention what is claimed is:—

A bottle having an opening therein surrounded by concentrically arranged inner 95 and outer radially spaced flanges of an appreciable depth, the opening being adapted to be closed by a seal having flanges crimped around the inner flange of the bottle, the outer edge of the outer flange extending beyond the inner flange and providing a base to support the bottle when the latter is sealed and the outer flange having an interrupted portion therein to permit of the insertion of an instrument beneath the flange of the seal. 100 105

In testimony whereof I affix my signature.

ELLIOTT B. CLARK,
